UNITED STATES PATENT OFFICE.

HENRY C. STAMM, OF MECHANICSBURG, PENNSYLVANIA.

WASHING-MACHINE.

1,185,140.

Specification of Letters Patent. Patented May 30, 1916.

Application filed September 14, 1915. Serial No. 50,640.

To all whom it may concern:

Be it known that I, HENRY C. STAMM, a citizen of the United States, residing at Mechanicsburg, in the county of Cumberland and State of Pennsylvania, have invented certain new and useful Improvements in Washing-Machines, of which the following is a specification, reference being had therein to the accompanying drawing.

10 This invention relates to certain new and useful improvements upon my patent for washing machine granted to me on March 30, 1915, Number 1,133,890, the object being to improve the general construction and to 15 provide means for mounting the plunger in such a manner that the same can be swung to one side of the tub when in raised position in order to allow the clothes to be inserted or removed therefrom.

20 Another object of my invention is to improve the general construction of plunger so as to increase the agitation of the clothes within the receptacle whereby the water will be forced through the mass of clothes in the 25 up and down stroke of the plunger.

Other and further objects and advantages of the invention will be hereinafter set forth and the novel features thereof defined by the appended claims.

30 In the drawings:—Figure 1 is a vertical section of my improved construction of washing machine showing the driving mechanism in elevation, and Fig. 2 is a detail perspective view of a portion of the receptacle showing the manner of mounting the driving mechanism to allow the same to be 35 swung to one side of the receptacle.

Like numerals of reference refer to like parts in the several figures of the drawings.

40 In the drawings, 1 indicates a main cylindrical receptacle mounted upon legs 2 so as to support the same in elevated position, said receptacle being formed of any suitable material and having a perforated 45 false bottom 3 arranged therein which is slightly spaced from the bottom of the receptacle 1, and on which is mounted a number of coil springs 4 in any suitable manner forming a yielding support for the supplemental receptacle 5 arranged concentrical within the outer receptacle 1, and provided with a perforated bottom 6, as clearly shown. The bottom of the receptacle 5 and the false bottom 3 are preferably provided 50 with studs over which the ends of the coil springs are arranged so as to hold the same

in the proper positions. The outer receptacle is provided with the usual drain 7, having a valve 8 constructed substantially as shown in my patent. An inlet T—9 is 60 also connected to the bottom of the outer receptacle to one branch of which is connected a steam pipe 10, provided with a valve pipe 11 for controlling the flow of steam and air therethrough, the other branch 65 of the T being provided with a water inlet 12 and a valve 13 for controlling the flow of water into the receptacle.

The outer receptacle 1 is provided with oppositely disposed outwardly projecting 70 pivot pins 14, on which are pivotally mounted supporting members 15 carrying arms 16 and 17, provided with tubular guides 16' and 17' in which are mounted guide rods 18, carrying bearing sleeves 19 at their upper ends which are pivotally mounted upon 75 bearings 20, formed on the ends of the cross bar 21, as clearly shown in Fig. 1.

The cross bar 21 is provided with a central threaded bearing 22 in which is mounted a threaded upper end 23 of a plunger rod 24, which is provided with a hand wheel 25 for revolving the same in order to adjust the position of the plunger rod within the bearing for the purpose herein- 80 after fully described. The lower end of the plunger rod 24 extends into a vertically disposed sleeve 26, carried by a head 27 which fits snugly within the inner receptacle 5, said sleeve being provided with oppositely disposed slots 28, through which extends a pin 29, carried by the plunger rod in order to allow the plunger rod to slide within the sleeve, the plunger rod being surrounded by a coil spring 30 between the 85 cross bar 21 and the upper end of the sleeve 26, as clearly shown, forming a yielding connection between the plunger rod and plunger head 27, so as to prevent the same 90 from being injured when the same is reciprocated through the driving mechanism 95 which will be later described.

The head 27 is provided with an annular depending flange 31 forming a vacuum cup having a valve 32, and arranged within the head is a series of vacuum cups 33, provided with valves 34 so as to allow the washing fluid to pass through the cups on the down stroke of the plunger and on the up stroke a partial vacuum is created within 105 said cup and head so as to draw the clothes within the inner receptacle upwardly 110

with the plunger in order to subject the clothes to a pounding action as well as to an agitation caused by the clothes being lifted up and down within the receptacle 5 by the vacuum action of the head.

In order to provide means for reciprocating the cross bar 21, I secure to the bottom of the outer receptacle 1, bearings 35, in which is mounted a drive shaft 36, provided with drive wheels 37 at its ends, carrying wrist pins 38, to which are connected pitman rods 39, the upper ends of which are pivotally mounted on the ends of the bearings 20, of the cross bar 21 as shown at 15 40. The drive shaft 36 is provided with a loosely mounted drive gear 41 having a female clutch portion 42 adapted to cooperate with a male clutch member 43, keyed on the shaft 36 and operated in the 20 usual manner so as to lock said drive gear 41 to the drive shaft 36 when it is desired to drive the mechanism in order to reciprocate the plunger, and by this construction the drive connection can be readily disconnected in order to stop the plunger on its 25 up stroke so that the same can be swung to one side of the receptacle to facilitate the inserting or removing of the clothes therefrom.

30 The lower ends of the supporting members 15 are provided with spring actuated pins 44 which coat with the sockets 45, having inclined faces so as to allow the pins to ride up said face into said socket when 35 the supporting members are thrown into vertical position so as to hold the guides rigid when the cross bar is in central position over the receptacle, and it will be seen by this construction the guides for the guide 40 rods 18 are so mounted that by drawing outwardly on the pins to release the supports, the cross bar can be swung laterally from over the center of the receptacle and as the pitman rods are pivotally connected 45 to the ends of the cross bar for moving on their bearings so as to allow the plunger to be swung laterally when in a horizontal plane.

From the foregoing description it will be 50 seen that I have provided a washing machine in which the reciprocating plunger is mounted within a cross bar, supported by guide rods mounted in removable bearings 55 in such a manner that said bearings can be swung laterally in respect to the receptacle

in order to remove the plunger when arranged in the plane of the receptacle laterally, so that the clothes can be readily inserted and removed from the tub, the driving connection being so connected to the 60 cross bar, that the bar is free to move when the wrist pins of the drive wheels are in raised position. It will also be seen that I have provided means for locking the removable supports in vertical position so as to 65 guide the plunger when being reciprocated in such a manner that all danger of the mechanism being injured is prevented.

What is claimed is:—

1. A washing machine, comprising a receptacle having oppositely disposed bearing pins and oppositely disposed sockets, supports pivotally mounted upon said bearing pins, guides carried by said supports, guide rods slidably mounted in said guides, a cross 70 bar connected to said guide rods, a plunger rod adjustably mounted in said cross bar, a plunger head slidably carried by said plunger rod, spring actuated pins carried by said supports coacting with the sockets for holding said supports in vertical position, and pitman rods connected to said cross bar for reciprocating the same.

2. In a washing machine, the combination with a receptacle, of movable supports 85 carried by said receptacle, means for locking said supports in vertical position, guides carried by said supports, guide rods slidably mounted in said guides, a cross bar having pivotal connection with said guide rods 90 at their upper end, a plunger rod carried by said cross bar, a plunger slidably carried by said plunger rod, and means for reciprocating said cross bar.

3. In a washing machine, the combination with a receptacle, of a reciprocating plunger mounted within said receptacle, a plunger rod connected to said plunger, a cross bar having connection with said plunger rod, guide rods pivotally connected to 100 said cross bar, movable supports carrying guides for said guide rods, means for locking said supports in adjustable position and means for reciprocating said cross bar.

In testimony whereof I hereunto affix my 105 signature in the presence of two witnesses.

HENRY C. STAMM.
